CLAIM

The ornamental design for a wine and spirits aerator, as illustrated and described.

DESCRIPTION

FIG. 1 is a bottom, front perspective view of a wine and spirits aerator showing my new design;

FIG. 2 is a top, front perspective view thereof;

FIG. 3 is a front view thereof, the rear view being identical;

FIG. 4 is a left side elevation view thereof, right side view being identical;

FIG. 5 is a bottom view thereof; and,

FIG. 6 is a top view thereof.

The broken lines in the drawings depict portions of the wine and spirits aerator that form no part of the claimed design.
